UNITED STATES PATENT OFFICE.

HOWARD K. KING, OF PHILADELPHIA, PENNSYLVANIA, ASSIGNOR TO CHAMBERS BROTHERS COMPANY, A CORPORATION OF PENNSYLVANIA.

OILING DEVICE FOR CLAY BARS.

1,180,653.

Specification of Letters Patent. Patented Apr. 25, 1916.

Application filed July 30, 1915. Serial No. 42,690.

To all whom it may concern:

Be it known that I, HOWARD K. KING, a citizen of the United States, residing at Philadelphia, in the county of Philadelphia, 5 State of Pennsylvania, have invented a new and useful Oiling Device for Clay Bars, of which the following is a specification.

My invention relates to improvements in oiling device for oiling the traveling clay bars, and is especially applicable to brick machines employing the wire side cutter. In such machines it is deemed desirable to have the bottom and one side of the bar lubricated before the same is acted upon by 15 the wires.

The object is to provide improved and efficient means for supplying exactly the right amount of lubrication to said surfaces without waste of the lubricant and without exposing the supply of oil to foreign substances.

Referring to the drawings, which illustrate merely by way of example, suitable means for the embodiment of my invention—Figure 1 is a side elevation showing my improved mechanism. Fig. 2 is an end elevation of same. Fig. 3 is a section on line 3—3 of Fig. 2. Fig. 4 is a section on line 4—4 of Fig. 3. Fig. 5 is a detail of parts shown in Fig. 1 on an enlarged scale. Fig. 6 is a section on line 6—6 of Fig. 5. Fig. 7 is a section on line 7—7 of Fig. 5.

Similar numerals refer to similar parts throughout the several views.

35 The oil reservoir 11 is suitably located at an elevation above the path of travel of the clay bar. Suitable conducting pipes 12 and 13 are connected with this reservoir. Plate 14 is mounted on the reel carriage or housing 10 and travels therewith. This plate 14 is recessed as at 15, and is provided with bevel edges adapted to coöperate with corresponding bevel edges of the plate 16, which is bolted thereto; there being clamped be-

45 tween said plates a suitable porous material 17 such as felt. The longitudinal margins of this felt are bent over and clamped between the sides of plate 14 and the lugs 18 of plate 16 thereby forming a tight seal all 50 around the margin of the felt 17. The ribs 19 are somewhat similar in construction to 18, but ending just short of the middle in space or chamber 20 which is formed in the body of plate 16 beneath said felt 15. These 55 ribs serve to support the felt in substantially

horizontal position. The chamber 20 is connected to the pipe 13 by which it is served with oil from the tank or reservoir 11. The pressure or supply of the oil delivered from reservoir 11 to chamber 20 is controlled by 60 a suitable needle valve 22, so that in operation a sufficient pressure of oil is delivered to chamber 20, to float or press the felt surface gently against the under surface of the moving clay bar, and just sufficient oil will 65 ooze through the felt to give efficient lubrication to said surface. The important feature in this arrangement is that by the proper adjustment of the needle valve the required pressure of oil in chamber 20 is 70 maintained, and consequently the required amount of oil is delivered through the felt to the clay bar without waste and also without undue exposure of the oil or the oiling surface. 75

For oiling a side surface of the bar I have provided a similar device illustrated in Figs. 5, 6 and 7 in which the cylinder 24 is mounted in a vertical position being closed at the top and bottom and provided along 80 one side with a series of apertures 25. Over this portion of the cylinder which is provided with the apertures 25, is clamped the body 26 of porous material, such as felt, between said cylinder and the side plate 27, 85 which side plate is recessed at 28 so that the outer surface of felt is made to project slightly beyond the surface of plate 27 so that as the bar moves along against said surface it will engage the felt 26. The oil 90 is delivered to cylinder 24 through the pipe 12 from reservoir 11; the supply being controlled by the needle valve 29. By properly locating and proportioning the apertures 25, and by properly controlling the supply of 95 oil by the valve 29, the required pressure of oil will be maintained in cylinder 24 and will be supplied through the felt 26 to the side surface of the clay bar 23.

In the embodiment of my invention above 100 described I have given felt as an example of a suitable body which is adapted to give a yielding pressure against the moving bar and is sufficiently porous or adapted to permit the oil to ooze therethrough to the surface of the bar. It will be understood however that I do not confine myself to this particular material, as obviously other material or materials or substances may be used with 105 similar results. 110

What I claim is:—

1. An oiling device for clay bars comprising a surface of porous material located in the path of travel of the bar, means for delivering oil to said material, and regulating means for controlling the pressure of the oil so that the required amount will be delivered through the material to the surface of the bar as the same moves in engagement therewith. 10
2. An oiling device for clay bars comprising a recessed slide plate, a recessed member clamped thereto, a porous fabric clamped between said plate and member, forming one side of a chamber or oil receptacle, its surface approximately corresponding to the supporting surface of the plate, means for delivering oil to said chamber whereby oil is delivered through the fabric to the 20 clay bar.
3. An oiling device for clay bars comprising a recessed slide plate, a recessed member clamped thereto, a porous fabric clamped between said plate and member, forming one side of a chamber or oil receptacle, its surface approximately corresponding to the supporting surface of the plate, means for delivering oil to said chamber whereby oil is delivered through the 25 fabric and the fabric is maintained in engagement with the moving clay bar.
4. An oiling device for clay bars comprising a recessed slide plate, a recessed member clamped thereto, a porous fabric clamped between said plate and member, forming one side of a chamber or oil receptacle, its surface approximately corresponding to the supporting surface of the plate, means for delivering oil to said chamber whereby oil is delivered through the fabric and the fabric has a tendency to be lifted slightly above the normal to insure efficient 30 yielding engagement with the clay bar and whereby undue wear is obviated.
5. An oiling device for clay bars comprising a recessed slide plate, a recessed member clamped thereto, a porous fabric clamped between said plate and member, forming one side of a chamber or oil receptacle, its surface approximately corresponding to the supporting surface of the plate, means for delivering oil to said chamber whereby oil is delivered through the fabric to the clay bar, and means for regulating the pressure of the oil to the required 35 supply.
6. An oiling device for brick machines comprising a slide plate having a narrow slot or recess in its face extending transverse the path of travel of the clay bar, a porous material projecting into or through said recess adapted to have yielding engagement with the surface of the clay bar, means 40 whereby oil is delivered to said porous material adapted to ooze therethrough to the clay bar, and means for controlling or regulating said oil delivery. 45
7. An oiling device for brick machines comprising a slide plate having a narrow slot or recess in its face extending transverse the path of travel of the clay bar, a porous material projecting into or through said recess adapted to have yielding engagement with the surface of the clay bar and means whereby oil is delivered to said porous material adapted to ooze therethrough to the clay bar, the oil pressure adapted to insure a gentle or yielding engagement between the porous material and the surface 50 of the clay bar. 55
8. Lubricating means for clay bars comprising a recessed side slide plate, a strip of felt or similar material clamped thereto over the recess and to project through the recess to engage the surface of the moving clay bar, and means whereby oil is delivered to the felt so as to ooze therethrough to the 60 surface of the clay bar. 65
9. An oiling device for clay bars comprising a slide plate having a recess transverse the path of travel of the bar, a porous material filling the recess having a surface for engaging the bar, and means for supplying oil to the porous material so that the same will ooze therethrough to the bar. 70
10. An oiling device for clay bars comprising a slide plate having a recess transverse the path of travel of the bar, a porous material filling the recess having a surface for engaging the bar, means for supplying oil to the porous material so that the same will ooze therethrough to the bar, and means for controlling or regulating the supply of oil, to secure the required pressure of the porous material against the bar 75 and the required supply of oil delivered thereto. 80
11. An oiling device for clay bars comprising vertical and horizontal slide plates, each provided with a recess transverse the path of travel of the bar, a porous material filling said recesses and adapted to project into said path of travel of the bar, and means for delivering oil to said porous material. 85
12. Means for oiling one surface of a rectangular moving bar comprising a body of yielding material adapted to press against said bar and so constituted as to permit oil to ooze therethrough to the engaging surface of the bar and means for delivering oil to said yielding body. 90
